UNITED STATES PATENT OFFICE

MICHAEL HALLWARD, OF PASADENA, CALIFORNIA

DESIGN FOR A CHILD'S CHAIR

Application filed October 10, 1932. Serial No. 45,268. Term of patent 7 years.

To all whom it may concern:

Be it known that I, MICHAEL HALLWARD, a subject of the King of Great Britain, residing at Pasadena, in the county of Los Angeles and State of California, have invented a new, original, and ornamental Design for a Child's Chair, of which the following is a specification, reference being had to the accompanying drawing, forming a part thereof.

Figures 1 and 2 of the accompanying drawing are perspective views of the child's chair of this design.

I claim:

The ornamental design for a child's chair, as shown.

MICHAEL HALLWARD.
